UNITED STATES PATENT OFFICE

LYNN B. CASE, OF NEW BRUNSWICK, NEW JERSEY, ASSIGNOR TO JOHN WALDON CORPORATION, OF NEW BRUNSWICK, NEW JERSEY, A CORPORATION OF NEW JERSEY

COATING MACHINE

Application filed July 26, 1930. Serial No. 471,022.

This invention relates to improvements in coating machines, and more particularly to machines intended for use in applying bakelite or similar coatings.

5 An important object of the invention is the provision in apparatus of this character of a construction permitting the production of a coated article wherein the coating is smoothly finished.

10 A further and more specific object of the invention is the provision in a machine of this character of a means for removing from the coating as applied by the ordinary coating rolls the small ridges and imperfections 15 which are always present in coatings applied by such rolls.

A still further object of the invention is to provide a doctor roll mechanism for use with coating machines to smooth the coatings applied thereby.

These and other objects I attain by the construction shown in the accompanying drawing wherein, for the purpose of illustration, I have shown a preferred embodiment of my 25 invention and wherein:

Fig. 1 is a side elevation of a coating machine embodying a doctor roll constructed in accordance with my invention;

Fig. 2 is a fragmentary perspective view of 30 the doctor roll; and

Fig. 3 is a plan view of the trough.

Referring now more particularly to the drawing, the numeral 10 generally designates the frame of a coating machine supporting 35 in bearings 11 and 12 rolls 13 and 14 which are employed in gauging the thickness of the coating remaining on the material being coated after its passage through the coating tank 15.

40 In accordance with my invention I mount upon the frame of the machine a pair of rolls 16 carried by a suitable bracket 17 which also mounts a doctor roll 18. The doctor roll 18 is mounted in bearings 19 adjustable 45 toward and away from the general plane of the faces of rolls 16 with which the coated material contacts. Roll 18 through chain and sprocket gearing 20 connecting the same with the roll 14, or through any other suitable driving medium, is driven at a speed

such that its surface speed is approximately five per cent of the speed of the material which is being coated. The bearings 19 through brackets 21 support a trough 22 having in the bottom thereof an opening for the passage of a wick 23 which contacts with the surface of roll 18. Trough 22 receives a solvent for the coating which is being applied and through the wick transmits this solvent to the surface of the roll 18. Since the surface speed of the roll is very low with respect to the treated material, the solvent acts upon the coating first to soften the same so that the smoothing action of the roll may remove any imperfections or roughnesses occurring therein. The solvent additionally serves to keep the surface of the roll clear.

Since the construction employed is obviously capable of a considerable range of change and modification without departing from the spirit of the invention, I do not wish to be understood as limiting myself to the particular structure herein illustrated except as hereinafter claimed.

I claim:

1. In coating apparatus, means for feeding a web to be coated and for applying a coating thereto, means for removing roughnesses from the coating comprising a doctor roll engaging the coated web, means driving said roll at a much lower surface speed than the speed of the web, and means for moistening the roll with a solvent of the coating material.

2. In coating apparatus, means for feeding a web to be coated and for applying a coating thereto, means for removing roughnesses from the coating comprising a doctor roll engaging the coated web, means driving said roll at a much lower surface speed than the speed of the web, a wick extending longitudinally of said roll and bearing thereagainst, and means for supplying a solvent of the coating to said wick.

3. In coating apparatus, means for feeding a web to be coated and for applying a coating thereto, means for removing roughnesses from the coating comprising a doctor roll engaging the coated web, means driv-

ing said roll at a much lower surface speed than the speed of the web, a trough supported adjacent to and extending longitudinally of the roll, and having a longitudinal aperture in its bottom, and a wick extending through said aperture and at its outer end engaging the roll.

4. In coating apparatus, means for feeding a web to be coated and for applying a coating thereto, and means for removing roughnesses from the coating comprising a member having a moving surface engaging the coated surface of the web, means for driving said moving surface at a speed considerably lower than the surface speed of the web, and means for applying a solvent of the coating to said surface of the member.

ing said roll at a much lower surface speed than the speed of the web, a trough supported adjacent to and extending longitudinally of the roll, and having a longitudinal aperture in its bottom, and a wick extending through said aperture and at its outer end engaging the roll.

4. In coating apparatus, means for feeding a web to be coated and for applying a coating thereto, and means for removing roughnesses from the coating comprising a member having a moving surface engaging the coated surface of the web, means for driving said moving surface at a speed considerably lower than the surface speed of the web, and means for applying a solvent of the coating to said surface of the member.
